UNITED STATES PATENT OFFICE.

JOSEPH J. SHERWOOD, OF ST. LOUIS, MISSOURI, ASSIGNEE TO HOOKER ELECTRO-CHEMICAL COMPANY, OF NEW YORK, N. Y., A CORPORATION OF NEW YORK.

ELECTROLYTIC METHOD AND APPARATUS.

1,427,236.

Specification of Letters Patent. Patented Aug. 29, 1922.

Application filed March 20, 1920. Serial No. 367,568.

To all whom it may concern:

Be it known that I, JOSEPH J. SHERWOOD, a citizen of the United States, residing at the city of St. Louis and State of Missouri, have invented certain new and useful Improvements in Electrolytic Methods and Apparatus, of which the following is a specification.

It is known that in the operation of electrolytic cells yielding a gaseous anode product at a substantially vertical face, there is a marked tendency, when relatively high anodes are used, for the upwardly rising gas to accumulate opposite the upper regions of the electrode in sufficient volume to reduce materially the active electrode surface, or the quantity of electrolyte available for carrying the current, and thereby to increase materially the operating voltage. A typical example of this is a cell for the production of caustic soda and chlorin by the electrolysis of sodium chlorid solutions, using vertical anodes of graphite. In such case it has been found preferable in high-amperage cells that the anodes should be of limited vertical height with reference to their horizontal extension, in order that the operating voltage for a given current density may be minimized. The above effect of the vertical height of the anode upon the energy efficiency of the cell is disclosed in Patent 1,075,570, patented October 14, 1913, to A. H. Hooker.

This objectionable characteristic of anodes of great vertical height may be in part overcome by diverting the chlorin or other gaseous product to the rear of the anode at regular intervals in its vertical height; but all such arrangements heretofore proposed, so far as I am aware, present the serious defect that if they are effective to divert the gas from the active anode face, they obstruct or otherwise interfere with the circulation of the brine which is necessary to maintain the concentration of the electrolyte at the proper degree in the interspace between the active electrode faces.

The present invention relates to a method and apparatus whereby the above objections are overcome, in such manner that the evolved gas may be withdrawn from the active anode face while at the same time brine of a proper concentration is directly supplied to such face.

A typical construction in accordance with this invention is illustrated in the accompanying drawing, wherein:

Figure 1 is a vertical section of an electrolytic cell intended primarily for the electrolysis of brine solutions and embodying my invention; and

Figure 2 is a plan view of a preferred form of gas-interceptor and brine distributor.

The electrolytic cell is illustrated as of the usual type comprising a cement body portion consisting of a horizontal bottom member 10, vertical end members 11 and a cover 12. These several members constitute an open-sided frame, to the sides of which are applied the perforated steel cathode plates 13 faced interiorly with asbestos paper or other suitable diaphragm material 14. The cathodes are enclosed by the usual recessed side plates 15 of steel, forming lateral cathode compartments 16, provided with bottom outlets 17 for the caustic solution, and top outlets 18 for hydrogen.

19, 19 represent the graphite anodes, shown as disposed parallel to the vertical cathodes 13 and adjacent thereto. 20, 20 are graphite posts, secured to and supporting the active anode plates 19, and constituting the current leads. In the form chosen for illustration these posts are supported on an insulating member 21 carried upon the base 10 of the cell, and extend vertically through the cover 12, terminating in metal caps 22 for connection to the anode buss-bars 23. The cathode buss-bars are indicated at 24. The upper ends of the anode posts may be enclosed in stoneware or other protective sleeves 25, and if desired a suitable plastic insulating compound 26 may be used as a seal to prevent gas leakage.

As clearly illustrated in the drawing, the anodes are provided at a point or points intermediate their height with channeled insulating members 27, one of which is illustrated in plan in Fig. 2. These members are advantageously made of stoneware, porcelain, glass or other appropriate insulating material, and preferably extend transversely the full width of the anode plate in such manner as to intercept and divert the rising gas bubbles, as most clearly indicated in Fig. 1. Preferably the gas interceptors will project through the interspace between the

electrodes into contact with the inner face of the diaphragms 14, as illustrated in this figure.

In the particular form chosen for illustration each gas interceptor is provided at the edge adjacent the cathode with a depending lip 28, which, together with the adjacent anode face, forms an inverted substantially horizontal or if preferred somewhat inclined gas channel 29, leading to a transverse duct 30 (Figs. 1 and 2), which extends from the front to the rear of the anode, and serves as will be readily understood to discharge the gas collected by the channel 29 at the rear anode face.

If desired the gas may be permitted to discharge freely into the electrolyte at the rear of the anode. It is preferred however, in order to avoid any substantial return of the gas to the active anode face, to provide a more or less defined channel through which the gas may be led to the surface of the electrolyte (indicated at 31) or even if desired to a point outside of the cell. One convenient means for accomplishing this result comprises short inclined tubes 32, which may be of glass, connecting with the ducts 30 and discharging the collected gas into vertical tubes 33, each of which may be provided if desired with a bottom collecting funnel 34. Obviously many other arrangements may be employed to secure the desired result.

As above pointed out it is not sufficient merely to divert the gas from the active anode face, but fresh electrolyte must be supplied directly to this face without mutual interference between the respective currents of gas and electrolyte. In the specific construction illustrated I accomplish this by the provision of a plurality of inclined ducts 35 (Figs. 1 and 2) traversing the insulating member 27 from the rear to a plurality of points adjacent the active anode face. Through these the electrolyte circulates rapidly in the direction indicated by the arrows to replace the depleted electrolyte entrained by the rearwardly moving gas stream. In this manner the necessary supply of fresh electrolyte at the regions of active electrolysis is assured.

My invention is not limited to the specific form and arrangement of parts chosen for illustration, inasmuch as these are susceptible of being modified in numerous ways without departing from the spirit of my invention. For example the gas interceptors may be supported by either or both of the electrodes, or independently of either electrode; and obviously the ducts communicating with the active electrode face may be formed wholly or partly within the body of the electrode, instead of wholly within the body of the gas interceptor as illustrated. These and

other modifications will be readily apparent to those skilled in this art.

I claim:

1. The herein-described electrolytic method comprising electrolyzing a solution yielding a gaseous product, diverting the evolved gas from the active electrode face at a point or points intermediate the top and bottom thereof; and simultaneously supplying fresh electrolyte directly to the active electrode face intermediate the top and bottom thereof, whereby interference of the inflowing electrolyte with the diversion of the gas is avoided.

2. In an electrolytic cell, the combination with an electrode having an upright active face, of means located intermediate the top and bottom of the electrode for diverting evolved gas from the active face thereof, and means for supplying electrolyte directly to the active electrode face intermediate the top and bottom thereof, whereby interference of the inflowing electrolyte with the diversion of the gas is avoided.

3. In an electrolytic cell, the combination with upright electrode members in spaced relation to each other, of a gas interceptor located between the electrode members and having a rearwardly extending gas duct.

4. In an electrolytic cell, the combination with upright electrode members in spaced relation to each other, of a gas interceptor located between the electrode members and having independent ducts for gas and electrolyte extending between the front and rear faces of the electrode.

5. In an electrolytic cell, the combination with an electrode having a substantially vertical active face, of a gas interceptor projecting from the active electrode face and having a rearwardly extending gas duct.

6. In an electrolytic cell, the combination with an electrode having a substantially vertical active face, of a gas interceptor projecting from the active electrode face and having independent ducts for gas and electrolyte extending between the front and rear faces of the electrode.

7. In an electrolytic cell, the combination with opposite upright electrodes each comprising a plurality of electrode members, of gas interceptors located between the electrode members and having rearwardly extending gas ducts.

8. In an electrolytic cell, the combination with opposite upright electrodes each comprising a plurality of electrode members, of gas interceptors located between the electrode members and having rearwardly extending gas ducts, and a conduit between the electrodes for conveying the gas to a point above the surface of the electrolyte.

In testimony whereof, I affix my signature.
J. J. SHERWOOD.
